BY Fisher & Mullan ATTYS.

UNITED STATES PATENT OFFICE.

VENDEL LÁSZLÓ BÉKEFI, OF CLEVELAND, OHIO.

ARMOR FOR AUTOMOBILE-WHEELS.

972,322:

Specification of Letters Patent. Patented Oct. 11, 1910.

Application filed February 19, 1910. Serial No. 544,909.

To all whom it may concern:

Be it known that I, VENDEL LÁSZLÓ BÉKEFI, citizen of the United States, residing at Cleveland, in the county of Cuyahoga and State of Ohio, have invented certain new and useful Improvements in Armors for Automobile-Wheels, of which the following is a specification.

My invention relates to armors for automobile wheels, and the invention consists in an armor made up of two series of plates mounted one upon the other and constructed and adapted to operate substantially as shown and described and particularly pointed out in the claim.

In the accompanying drawings, Figure 1 is a side elevation of a section of a wheel upon which my improved armor is shown in working position. Fig. 2 is a longitudinal section of two of said plates and Fig. 3 is a cross section thereof. Fig. 4 is a perspective view of one of the outer plates and Fig. 5 is a perspective view of one of the inner plates.

The invention as thus shown is an improvement upon the construction of armor shown and claimed in my patent issued June 16, 1908, No. 891,830. In the said patent the plates are single and adapted to overlap at their ends, and are smooth internally and externally. They also are heaviest or deepest at their middle longitudinally and recessed transversely over one end each so as to lap the end of the next succeeding plate thereover and make a uniform outside or peripheral surface on the tread of the wheel.

The present invention is made to overcome the objection to my patented armor in this, that if one of those plates become impaired it had to be thrown away and a new one be substituted in its entirety. This made the armor unduly expensive because I found that such injuries were quite frequent. Hence I conceived the idea of building an armor with a dual construction and in which there is a permanent inner plate A and an outer service plate B removably fixed thereon. The latter is distinctly a road contact plate which wears out sooner or later and is intended to be replaced when this occurs. To this end the said plate is provided with transverse corrugations 2 which are deepest at the center and take the immediate exposure to the road. Said plates, like inner plates B, are of suitable metal, and

the outer plate lies upon the inner plate relatively as shown and is secured thereto by screws 3 or their equivalent. The outer plate overlaps the inner plate at one end and the inner plate projects beyond the outer plate at the other end in the same proportion, so that the outer plates will always overlap the joints of the inner plates, or the two sets of plates will break the joints as shown. The inner plates are secured upon tire T by turnbuckle connections 4 at each side engaging with chains C at the side of the rim as shown.

The plate B is preferably made out of a piece of sheet steel bent substantially half round in cross section and adapted to fit snugly over tire tube T. Said plate therefore is of uniform thickness throughout and comparatively light in weight, while plate A is of suitable cast metal, preferably, though it might be struck up from sheet metal with more or less pronounced ribs 2. The inner plates B also have narrow exposed edges 7 at each side extending outward beyond plates A and turnbuckles 4 are attached thereto, two for each side near the ends of said plates. It follows that a complete unitary part made according to my invention consists of two plates A and B fastened together and arranged in respect to each other relatively as shown, one end of each plate projecting beyond the corresponding end of the other plate and said plates adapted to match with the next pair of plates at both ends as hereinbefore described.

To facilitate traction purposes, especially in climbing hills, the transverse ribs 2 of plate A are preferably of ratchet like tooth formation as shown in cross section in Fig. 2.

Plate B is preferably struck up outwardly to form an offset or recess b at the point where the pivoted connection of turn-buckle 4 is made, the object being to keep said connection out of contact with the rubber tire 100 and prevent wear and abrasion thereof.

With the use of this invention, tires as ordinarily constructed may be materially lightened and made thinner especially at the tread portion thereof, and there is also a saving of power in driving a machine because of the excellent traction results to be obtained by its use.

What I claim is:

An armor for pneumatic wheel tires con-

110

sisting of a multiplicity of members oper-
atively overlapping at their ends and each
member constructed of inner and outer parts
separably united, both said parts segmen-
tally shaped in cross section and each part
projecting at one end beyond the end of the
other part corresponding therewith, said
inner member provided with projections at
its sides having holes through which fasten-

ing means for holding said parts on a wheel 10
are adapted to be connected.

In testimony whereof I affix my signature
in presence of two witnesses.

VENDEL LÁSZLÓ BEKEFI.
